UNITED STATES PATENT OFFICE.

BENJAMIN J. GUDGE, OF WILKINSBURG, PENNSYLVANIA, ASSIGNOR TO WESTINGHOUSE ELECTRIC & MANUFACTURING COMPANY, A CORPORATION OF PENNSYLVANIA.

SHEET-WINDING MACHINE.

Application filed December 31, 1918. Serial No. 269,095.

To all whom it may concern:

Be it known that I, BENJAMIN J. GUDGE, a citizen of the United States, and a resident of Wilkinsburg, in the county of Allegheny and State of Pennsylvania, have invented a new and useful Improvement in Sheet-Winding Machines, of which the following is a specification.

My invention relates to sheet-winding machines and it has for its primary object the provision of a machine to be employed for quickly and easily winding a sheet of any desired material about a small mandrel which may be subsequently removed.

In the electrical arts, composite rods of insulating material have been formed by winding suitable sheet material, impregnated with a desirable binder, about a small mandrel, or about a crimped edge of the sheet to provide a body or roll of superimposed layers. The mandrel, if any was employed, was then removed and the roll was cured, under pressure, to form a strong solid rod of insulating material. Among many suitable sheet materials which have been employed, paper has been found to be very satisfactory and, while various binders have been utilized, a phenolic condensation product, such as the well known bakelite, has proved particularly well suited for the purpose.

When forming rods of impregnated sheet material of this character, it is very desirable that such impregnated material shall be wound as closely and compactly as possible and that the mandrel, if any be employed, shall be as small as possible, in order to decrease, to a maximum degree, the amount which the wound body of paper must be reduced in volume by compression, during curing, to insure the requisite density in the finished rod. Because of the small size of mandrels found necessary for this reason, it has been customary, heretofore, to wind the sheet material about the mandrels by hand, as no machine, previously known, was capable of accomplishing this work suitably. Hand winding is very slow and tedious and it has been almost impossible to obtain closely wound bodies or to insure uniformity, in the winding, such as will prevent crumpling of the wound material in a mold.

One of the objects of my present inven-

tion resides in providing a machine capable of winding paper or other suitable sheet material upon an extremely small mandrel in a rapid and efficient manner.

A still further object of my invention is to provide a machine of this character having a two-part mandrel between the parts of which one end of the sheet to be wound may be positioned so that the sheet will be held against slipping during the winding action, with the result that tension may be applied to the sheet to insure its being wound with any desired degree of closeness.

In this connection, a still further object of my invention consists in providing a driving mechanism comprising correspondingly driven, alined chucks capable of detachably receiving the ends of the mandrel sections and of holding the mandrel sections in proper relative positions when they are in place.

With these and other objects in view, my invention will be more fully described, illustrated in the drawings, in the several views of which corresponding numerals indicate like-parts, and then particularly pointed out in the claims.

In the drawings, Fig. 1 is a front elevational view of my improved machine; Fig. 2 is a vertical sectional view taken substantially on the line II—II of Fig. 1; Fig. 3 is an elevation of one of the mandrel-receiving chucks, and Fig. 4 is an end view of the same chuck.

One embodiment of my invention, as shown in the drawings, includes a suitable support or table 1 carrying bearing brackets 2, which may preferably be disposed near opposite edges of the table and in which are journalled alined shaft sections 3 and 4. That end of the shaft section 3 nearer the shaft section 4 comprises a pair of spaced, longitudinal recesses or sockets 5, as best shown in Fig. 2 of the drawings. The corresponding end of the shaft section 4 is formed with a radial slot 6 opening through its side and end and a retaining sleeve 7 is mounted about the slotted end of the shaft section. This sleeve is held against longitudinal movement upon the shaft section by a pin 8 carried by the shaft and projecting through a slot 9 formed in the sleeve in such a manner as to permit partially turning

of the sleeve with respect to the shaft. The sleeve is formed with a longitudinal slot 10 adapted, in one position, to align with the radial slot 6 of the shaft section.

5 The ends of the shaft sections, when fitted in this manner, constitute, in effect, opposed chucks capable of detachably receiving a winding mandrel 11. This mandrel, as best shown in Figs. 1, 3 and 4, comprises a pair 10 of relatively small rods or wires 12 which are preferably resilient and may be desirably formed of steel, or equivalent material, in order that they may possess maximum strength, relative to their small diameters.

15 In practice, the rods or wires 12 are inserted, at one end, in the recesses or sockets 5 of one chuck and their opposite ends are slipped through the slot 10 of the sleeve 7 and into the radial slot 6 of the other chuck 20 after which the sleeve is partially turned to lock them against displacement.

As a means for rotating the chucks and the mandrel carried by them, I may provide any suitable source of power, such as an electric motor 13. Upon the shaft of this motor 25 may be mounted a pulley 14, and a belt 15 may be passed about this pulley and about a pulley 16 carried by one of the aligned shaft sections, as, for example, the shaft sections 30 3. Gear wheels 17 may be fixed to the shaft sections and may mesh with pinions 18 fixed upon a shaft 19 which may preferably be journaled in bearing-brackets 20 secured to the under side of the table 1.

35 Obviously, with this arrangement, the two chucks will be simultaneously driven, in the same direction and at the same speed.

40 As it is desirable to be able to stop the turning of the chucks and mandrel at frequent intervals, I preferably make the belt 15 loose so that it will not normally transmit power from the motor to the shaft section 3 and provide a belt tightener which 45 may be operated in any suitable manner to tighten the belt and cause transmission of power from time to time, as may be desired. Any suitable type of tightener may 50 be employed, one being clearly shown in Fig. 2 as comprising an idler pulley 21 engaging the belt and carried at one end of a lever 22 which is pivoted, between its ends, upon a bracket 23. A cord 24 or other flexible connection may be secured, at one end, to the free end of the lever 22 and, at its 55 opposite end, to a pivoted treadle 25, located at any convenient point, the cord being preferably passed over suitably located guide pulleys 28.

60 From the foregoing description, the method of employing my machine and the manner in which it operates will be readily understood and only a slight explanation is, therefore, necessary. Preferably, a stack of the sheets to be wound is placed upon the 65 table at the rear of the mandrel. The operator

may then pass the nearer end of the uppermost sheet between the mandrel sections or rods 12, and start the machine by pressing the treadle to operate the belt tightener. Under these circumstances, the mandrel will 70 be rapidly turned and, as a result, the sheet will be wound about it. The operator may readily govern the tightness with which the sheet will be wound by grasping the mandrel and the sheet being wound thereon with 75 more or less closeness during the winding operation.

After the sheet has been wound, the sleeve 7 may be turned to permit disengagement of the adjacent end of the mandrel which, in 80 turn, will permit disengagement of its opposite end. The mandrel may then be removed and its sections may be withdrawn from the wound roll in any suitable manner, such as by engaging the ends of the sections 85 in a vise or clamp of suitable construction. The mandrel sections may then be again engaged between the chucks and the operation above described may be repeated.

90 Preferably, I provide a multiplicity of interchangeable mandrel sections in order that the operator need not pause between the winding of successive sheets to withdraw the mandrel sections. Also, in order to facilitate the rapidity of operation, suitable 95 spring clips or similar devices may be provided which may be engaged about the rolls as they are finished to hold the sheet against unwinding until the mandrel sections have 100 been removed and the roll has been placed in a mold for final treatment.

From actual employment of such a machine, I have found that it is possible to greatly decrease the time required in the manufacture of rods of this character and, 105 consequently, to decrease the cost of their manufacture. Furthermore, operators, not as highly skilled as those previously required, may do efficient and rapid work by employing my machine and may secure much 110 more uniform results than were possible, even by the more skilled operators, when the rolls were formed by hand.

Obviously, numerous modifications and changes may be made in the machine to suit 115 various circumstances and conditions. For example, if semi-cylindrical mandrel sections are employed, the machine may be utilized to wind sheet material into tubes and, upon removal of the mandrel sections, 120 a solid mandrel of cylindrical or other desired shape may be inserted in the wound tube to support it while it is molded. Because of these possible changes, no limitations are to be imposed upon my invention 125 other than those indicated in the claims.

I claim as my invention:

1. A sheet-winding machine comprising opposed, driven chucks and a mandrel detachably engaged by the chucks, the mandrel 130

including a pair of separately removable and substantially parallel spaced members between which the edge of the sheet may be inserted.

- 5 2. A sheet-winding machine comprising a pair of opposed and correspondingly driven shaft sections, one of which is provided with spaced recesses and the other of which is provided with a radial slot, a pair of resilient mandrel sections adapted to engage, at one end, in the recesses and, at the opposite end, in the slot, and means for retaining the latter ends of the members in the slot.
- 10 3. A sheet-winding machine comprising a pair of opposed, correspondingly driven chucks, and a mandrel detachably received

by the chucks and comprising spaced substantially parallel and separable sections.

4. A sheet-winding machine comprising a pair of revolvably mounted chucks, a mandrel detachably engageable by the chucks, a driven shaft, pulleys upon the driven shaft and one of the chucks, a loose belt passed about the pulleys, manual means for tightening the belt and thus driving said shaft, and means for transmitting power from the first chuck to the other.

In testimony whereof, I have hereunto subscribed my name this 17th day of Dec. 1918.

BENJ. J. GUDGE.
